BACON PACKAGE

Kenneth T. Buttery and Thomas Vander Lugt, Jr., Kalamazoo, Mich., assignors to Sutherland Paper Company, Kalamazoo, Mich.

Application February 6, 1959, Serial No. 791,587

7 Claims. (Cl. 229—40)

This invention relates to improvements in packaging cartons, including cartons desirable for packaging products such as sliced bacon and the like. The main objects of this invention are,

First, to provide a carton well adapted for packaging food products such, for example, as sliced bacon, which is of generally parallelogram contour viewed endwise and at the same time effectively resists load or crushing stresses.

Second, to provide a carton having these advantages which may be formed of a single cut and scored blank of container board of relatively light stock, and at the same time is strong and rigid when erected and may be repeatedly handled without distortion.

Objects relating to details and economies of the invention will appear from the description to follow. The invention is defined and pointed out in the claims.

A preferred embodiment of the invention is illustrated in the accompanying drawing in which:

Fig. 1 is a front perspective view of an erected carton embodying our invention.

Fig. 2 is an end elevational view with a portion of the outer end wall member broken away to show structural details.

Fig. 3 is an enlarged vertical section on a line corresponding to line 3—3 of Fig. 2.

Fig. 4 is an enlarged fragmentary view on a line corresponding to line 4—4 of Fig. 1.

Fig. 5 is a plan view of the blank, the scoring thereof being indicated by dotted lines. The window opening in the blank is illustrated as provided with a transparent closure which is in practice separate from the body member of the blank.

In the accompanying drawing we have illustrated our invention as embodied in a carton particularly designed for the packaging of sliced bacon and the like in which the slices are arranged in an inclined relation. We have not illustrated any contents in the accompanying drawings as they form no part of our present invention and our carton is adapted for and desirable in the packaging of food products other than sliced bacon.

The embodiment of our invention illustrated comprises a bottom 1, front wall 2, inner rear wall member 3 adjustably connected to the bottom by the scores 4. The top 5 is hingedly connected to the upper edge of the front wall 2 by the hinges 6. The outer rear wall member 7 is hingedly connected to the top by the folding or hinging scores 8. The outer rear wall member 7 has a sealing flap 9 hingedly or foldably connected to the outer edge thereof by the score 10.

In the embodiment illustrated a window opening 11 is formed in the top and extends into the upper edge of the front wall, and as illustrated is provided with a transparent closure 12. The ends comprise the inner end wall members 13 of parallelogram contour which are hingedly connected to the ends of the bottom at 14. The inner end wall members and the front wall have inwardly foldable corner flaps 15 having folding scores

2

16 therein, said corner flaps being hingedly connected to the rear ends of the inner wall members 13 and to the ends of the front wall by the folding scores 17.

The top 5 has outer end wall extensions 18 on its ends hingedly connected thereto at 19 and positionable on the outer side of the inner end wall member 13. Inwardly foldable corner flaps 20 connect the rear ends of the outer end wall members to the ends of the outer rear wall member. These fold inwardly in the same manner as the corner flaps connecting ends of the front wall to the inner end wall members. The sealing flap 9 is desirably adhesively secured throughout the length thereof to the under side of the bottom, the adhesive however not being illustrated. The sealing flap 9 is provided with struts 21 on its ends which when the carton is erected are positioned between the inner end wall members 13 and the outer end wall members 18, as illustrated in Fig. 3. These struts when erected engage the top as is illustrated and are positioned to resist downthrust such as results from stacking a plurality of cartons or other load on the carton which would tend to collapse it as a result of its parallelogram shape. The inner end wall member 13 also resists such collapsing and the corner members coact to that end, but these struts add greatly to the strength of the carton.

While we have illustrated our invention as embodied in a carton of parallelogram section or shape, our invention may be embodied in rectangular cartons. The sealing flap lapped upon and secured to the bottom also acts as a reinforcing element to resist collapsing stresses and enables the use of lighter stock than would otherwise be practical.

We have illustrated and described our invention in a highly practical embodiment thereof. We have not attempted to illustrate or describe other embodiments or adaptations as we believe this disclosure will enable those skilled in the art to embody or adapt our invention as may be desired.

Having thus described the invention, what is claimed as new and desired to secure by Letters Patent is:

1. A carton having a generally parallelogram transverse contour when erected formed integrally of paper-board cut and scored to provide a bottom, a front wall at one side edge of the bottom and an inner rear wall panel at its other side edge, a top hingedly connected to the upper edge of the front wall and having an outer rear wall panel on its swinging edge dimensioned to overlap said inner rear wall panel, said outer rear wall panel having a sealing flap on its outer edge adapted to be lapped upon and fixedly secured to the under side of the bottom, inner end wall members of parallelogram contour hingedly connected to said bottom, said inner end wall members and said front wall having inwardly foldable corner flaps hingedly connected thereto, outer end wall members hingedly connected to said top for positioning in overlapping relation to said inner end wall members, said outer end wall members and said outer rear wall panel having inwardly foldable corner flaps hingedly connected thereto and to each other, said sealing flap having upturned struts at its ends retainingly disposed between the said inner and outer wall members when the carton is erected in supported engagement with the top.

2. A carton having a generally parallelogram transverse contour when erected formed integrally of paper-board cut and scored to provide a bottom, a front wall at one side edge of the bottom and an inner rear wall panel at its other side edge, a top hingedly connected to the upper edge of the front wall and having an outer rear wall panel on its swinging edge dimensioned to overlap said inner wall panel, said outer rear wall panel having a sealing flap on its outer edge adapted to be lapped upon and fixedly secured to the under side of the bottom, inner

end wall members of parallelogram contour hingedly connected to said bottom, outer end wall members hingedly connected to said top for positioning in overlapping relation to said inner end wall members, said sealing flap having upturned struts at its ends retainingly disposed between the said inner and outer wall members when the carton is erected in supported engagement with the top.

3. A carton comprising a bottom, a front wall on one side edge of the bottom and an inner rear wall member on its other side edge, a top hingedly connected to the upper edge of the front wall and having an outer rear wall member on its swinging edge overlapping said inner wall member, said outer rear wall member having a sealing flap on its outer edge adapted to be lapped and secured upon the under side of the bottom, inner end wall members hingedly connected to said bottom, said inner end wall members and said front wall having inwardly foldable corner flaps hingedly connected thereto and to each other, outer end wall members hingedly connected to said top for positioning in overlapping relation to said inner end wall members, said outer end wall members and said outer rear wall panel having inwardly foldable corner flaps hingedly connected thereto and to each other, said sealing flap having upturned struts at its ends retainingly disposed between the said inner and outer end wall members when the carton is erected and said sealing flap is secured to the bottom in lapping relation thereto with the upper ends of the struts in downthrust supported engagement with the top.

4. A carton comprising a bottom, a front wall on one side edge of the bottom and an inner rear wall member on its other side edge, a top hingedly connected to the upper edge of the front wall and having an outer rear wall member on its swinging edge overlapping said inner wall member, said outer rear wall member having a sealing flap on its outer edge adapted to be lapped and secured upon the under side of the bottom, inner end wall members hingedly connected to said bottom, outer end wall members hingedly connected to said top for positioning in overlapping relation to said inner end wall members, said sealing flap having upturned struts at its ends retainingly disposed between the said inner and outer end wall members when the carton is erected and said sealing flap is secured to the bottom in lapping relation thereto with the upper ends of the struts in downthrust supported engagement with the top.

5. A carton comprising a bottom, opposed side walls, a top hingedly connected to the upper edge of one of the side walls and having an outer side wall member on its swinging edge overlapping the other side wall, said outer side wall member having a sealing flap on its outer edge adapted to be lapped and secured upon the under side of the bottom, inner end wall members hingedly connected to said bottom, said inner end wall members and

5 said front wall having inwardly foldable corner flaps hingedly connected thereto and to each other, outer end wall members hingedly connected to said top for positioning in overlapping relation to said inner end wall members, said outer end wall members and said outer rear wall panel having inwardly foldable corner flaps hingedly connected thereto and to each other, said sealing flap having upturned struts at its ends retainingly disposed between the said inner and outer wall members when the carton is erected and said sealing flap is secured to the bottom in lapping relation thereto with the upper ends of the struts in downthrust supported engagement with the top.

10 6. A carton comprising a bottom, opposed side walls, a top hingedly connected to the upper edge of one of the side walls and having an outer side wall member on its swinging edge overlapping the other side wall, said outer side wall member having a sealing flap on its outer edge adapted to be lapped and secured upon the under side of the bottom, inner end wall members hingedly connected to said bottom, outer end wall members hingedly connected to said top for positioning in overlapping relation to said inner end wall members, said sealing flap having upturned struts at its ends retainingly disposed between the said inner and outer wall members when the carton is erected and said sealing flap is secured to the bottom in lapping relation thereto with the upper ends of the struts in downthrust supported engagement with the top.

15 7. A carton of generally parallelogram transverse contour when erected comprising a bottom, a front wall hingedly connected to the front edge of the bottom, a rear wall panel hingedly connected to the rear edge of the bottom, a top hingedly connected to the upper edge 20 of the front wall and having an outer rear wall panel hingedly connected to its swinging edge and dimensioned to overlap said inner rear wall panel, said outer rear wall panel having a sealing flap on its outer edge adapted to be lapped upon and fixedly secured to the under side 25 of the bottom, inner end wall members of parallelogram contour hingedly connected to the bottom, and outer end wall members hingedly connected to said top for positioning in overlapping relation to said inner end wall members, said sealing flap having strut members on its ends positionable between said inner and outer end wall members and dimensioned to supportedly engage the top.
